CABINET FOR SCIENTIFIC EQUIPMENT Theodore Overman Pollard, Palo Alto, Calif., assignor to
International Plasma Corporation

Filed Aug. 19, 1968, Ser. No. 13,171

Term of patent 14 years

Int. Cl. D14—02

U.S. Cl. D26—5

FIG. 1

FIG. 2

FIG. 3

FIG. 4

FIG. 5

FIG. 6

FIGURE 1 is a perspective front view of a cabinet for scientific equipment embodying my invention;

FIGURE 2 is a back elevation of the cabinet shown in FIGURE 1;

FIGURE 3 is a bottom plan view of the cabinet;

FIGURE 4 is an end elevation of the cabinet embodying my invention and is substantially the same as the opposite end elevation;

FIGURE 5 is a perspective front view of the cabinet similar to that of FIGURE 1 but with the front panel shown in a raised position; and

FIGURE 6 is a perspective rear view of an alternative cabinet embodying the ornamental design of my invention herein identical in all other views to that of the one cabinet shown in the foregoing figures.

The dominant features of the design reside in the full line portions.

I claim:

The ornamental design for a cabinet for scientific equipment, as shown and described.
